STRENGTH-TESTING MACHINE

John G. Jansen, Chicago, Ill.

Application August 27, 1940, Serial No. 354,438

9 Claims. (Cl. 265—22)

My invention relates to strength testing machines of the type which are coin-controlled, and which contain means for muscle, grip and pull-up tests, and my main object is to devise a machine which provides two degrees of resistance for the several tests, so that children and persons of light weight or build may encounter a given range of resistance, while men or more robust persons may encounter a range of higher resistance.

A further object of the invention is to accomplish the above object by simple means which are applied or excluded by the actuation of a small control in front of the machine.

Another object of the invention is to join means for the various tests in a manner to operate harmoniously with a minimum of parts and be compactly grouped.

An important object of the invention is to design the novel machine with units which are sturdily built and follow efficient mechanical principles.

With the above objects in view and any others which may suggest themselves from the description to follow, a better understanding of the invention may be had by reference to the accompanying drawings, in which—

Fig. 1 is a front elevation of the machine;

Fig. 2 is a top plan view;

Fig. 3 is a right-hand part sectional side view of the main portion of the machine, showing its interior;

Fig. 4 is a view similar to Fig. 3, taken from the left-hand side;

Fig. 4a is a bottom supplement of Fig. 4 on a reduced scale;

Fig. 5 is a section on the line 5—5 of Fig. 3;

Fig. 6 is a section on the line 6—6 of Fig. 5;

Fig. 7 is a duplication of the left-hand upper corner of Fig. 6, in the form of a section taken substantially on the line 7—7 of Fig. 3; and

Fig. 8 is a section on the line 8—8 of Fig. 7.

Referring specifically to the drawings, 10 denotes the housing of the machine, the same having a tall base 11. When approaching the machine from the front, two laterally-spaced knobs 12 are seen, these having shanks 13 passing through arcuate slots 14 in the front wall of the housing. The knobs are called the muscle tester, and intended to be pressed toward each other to actuate a pointer 15 visible through a glass front 16 and operable in relation to a scale 17 in terms of pounds or other suitable units of pressure. Below the muscle tester is an arched bar 18 in cooperation with which a horizontal

stem 19 formed with a vertical cross-pin 20 is adapted to be drawn from the full line to the dotted line position in Fig. 4. This is called a grip test, and a suitable connection within the machine transmits the action to the pointer 15. Below and in front of the base 11 is a stand 21 in which a rod 22 is vertically disposed and capped with a handle 23. The latter is for the pull-up test, suitable connections from the rod 22 extending to the pointer 15 to register this action. The testing units so far described, and their relative positions are conventional in machines of this type, and are therefore not broadly new.

In relation to the muscle tester, the shanks 13 thereof extend into the front of the machine to be rigidly connected to a pair of sturdy arms 25. Each of these arms is formed with a T-base 26, the junction with which receives a screw 27 directed into the front of the housing to pivotally dispose the arm 25 within the same. The outer end of each base 26 is bifurcated as indicated at 26a to receive a cross-pin 28 on which is suspended the upper-end 29 of a vertical coil spring 30. The right-hand spring 30, as seen in Fig. 5—is connected at its lower end 31 to a hook 32 which is formed as a screw 33 to be adjustable in a socket 34 secured to a front-wall shelf 35. The left-hand spring 30, however, is not made fast at its lower end, but simply is connected thereto to a light coil spring 36 whose lower end is secured to a pin 37 projecting from the front wall of the housing. Thus, when the knobs 12 are gathered, such as from the full line position in Fig. 6 toward the dotted line position in the same figure, the arms 25 will rock toward each other on the pivots 27, the right-hand arm drawing upon the related spring 30 for resistance to the action, and the left-hand spring 30 simply drawing on the light spring 36. The purpose of the latter is to hold the related spring 30 in a substantially vertical position normally or during the test just described. However, I have added a second hook 38 like the hook 32 but with a plain side bend for its head, such head being opposite the lower end of the related spring 30. Thus, should this spring be pushed toward the right, its lower end will lie under the head of the hook 38. Then, when the test is applied the resistance will be doubled through the inclusion of the left-hand spring 30 in the resistance.

Relative to the grip tester 20, the stem 19 thereof enters the housing to take the form of a slide 40. This slide operates along an angle bar 41 projecting rearwardly from the front wall

of the housing and braced by an upright 42 bolted at 43 to a rib 44 rising from the floor or bottom 45 of the housing. The slide 40 has an abutment 46 as its rear motion limit, the abutment being secured to the angle bar 41 by a screw 47. The side of the bar 41 is made with a horizontal slot 48 through which a bolt 49 carried by the slide passes to receive a nut 50 at its outer end. A coil spring 51 is connected between the bolt 49 and a hook 52, the hook having a screw shank 53 passing through a bracket 54 to receive a securing nut 55, the bracket being connected by a screw 56 to the junction of a horizontal frame bar 57 with the upright 42. It will now be apparent that drawing the cross-pin 20 forward for the grip test will pull on the spring 51 for resistance.

In the above case, also, a double resistance is provided by the addition of a companion spring 58 more clearly seen in Fig. 3. The rear end of this spring is connected by a bracket 59 to the screw 56 at the junction previously referred to, while the front end of the spring 58 is connected to an arm 61 which is mounted loosely at the bottom on a bolt 62 which passes through the rib 44 to receive a securing nut 63. A spring 64 is inserted between the arm 61 and the head of the bolt, whereby to enable the arm to pivot away from the rib 44 without becoming loose. The arm is drawn away from the rib by a coil spring 65 whose remote end is connected at 66 to a bracket 67 extended from the frame bar 57. The arm 61 terminates with a finger 68 at the top which, according to the normal position of the arm 61 is at one side of a block 69 carried by the slide 40. Thus, should the arm 61 be moved toward the slide against the tension of the spring 65, the finger 68 will assume a position directly in front of the block 69. Now, when the grip test is taken, the forward motion of the slide will also draw, through the medium of the arm 61, on the companion spring 58, doubling the resistance to the grip. Incidentally, the arm 61 would now pivot from the rear to the front on the bolt 62.

As to the pull-up test, the rod 22 is noted in Fig. 4a as depending into the frontal stand 21, making connection at its lower end with an arm 70 which is medially pivoted at 71 in a standard 72. The rear end of the arm 70 is connected to an upright rod 73 in a manner to draw downwardly upon the same when the pull-up handle 23 in front is actuated. Fig. 4 shows more clearly that the downward action of the rod 73 is resisted by a large spring 74 coiled around the rod between securing means 75 near the top thereof and the floor 45 of the housing 10. The upper end portion of the rod 73 makes a pivotal connection 76 with one end of a cam 77, the medial portion of the cam being horizontally pivoted on a bolt 78 driven into the angle bar 41. The profile of the cam 77 is opposite a peripherally-grooved nut 79 mounted on the bolt 49, so that the counter-clockwise rotation of the cam 77—as viewed in Fig. 4—in response to the downward motion of the rod 73 will impinge forwardly on the bolt 49 to move the slide 40 accordingly. Since this movement is resisted by the spring 51, the pull-up test will involve both the springs 74 and 51. Also, the application of the companion spring 58 as described before will provide the extra resistance for the pull-up test.

The change from the single to the double resistance for the testing units is controlled by a ring 80 whose normal position is close to the front of the housing as indicated by full lines in

Fig. 3, but which may be drawn forward to the dotted line position in the same figure when the change is desired. The ring 80 is at the front end of a horizontally positioned U-shaped rod 81 whose arms are slideable in the bracket 67 extended from the frame bar 57. Fig. 6 shows the rod 81 in its rear position by means of full lines. It is apparent that the arms of the rod are peripherally-grooved at 82 near the back of the rod. Thus, when the rod is drawn forward by means of the ring 80 to the dotted line position in Fig. 6, the grooved portions 82 are designed to catch in the bracket 67 and form stops for the forward motion of the rod. Of course, these stops are not positive, as they will yield to rearward pressure upon the ring 80 when the same is to be restored to its original position.

The left-hand arm of the rod 81—as seen in Figs. 5 and 6—carries a blade 83 from which is projected a V-shaped arm 84 whose forward end is close to the left-hand side of the left-hand spring 39. When the ring 80 is pulled forward, the arm 84 advances to bear on the side of the spring 39 in the manner of a cam, so that when the arm 84 is in the dotted line position of Fig. 6 it has pushed the spring 39 toward the right to engage the hook 38 and furnish the double resistance to the gathering of the muscle-test arms 25, as previously described.

The other, or centrally located arm of the rod 81 is made with a flat and tapering end portion 85, as shown in Fig. 7, this portion of the arm lying against the left-hand side of the arm 61. Thus, when the rod 81 is pulled forward by the ring 80, the tapered portion 85 bears on the arm 61 in the manner of a cam to force it to the position in front of the slide block 69 as indicated by dotted lines in Fig. 8. Now, the companion spring 58 is brought into play for the doubled resistance to the grip test and added resistance to the pull-up test, as previously described.

The pointer 15 is mounted on a spindle 90 journaled in brackets 91 and 92 attached to the front wall of the housing. Inwardly of the bracket 91, the spindle carries a disk 93 whose hub 94 is rigidly secured to the spindle by a set screw 95. A spring 96 extends from the set screw to a suitable bracket hook 97 for the purpose of resisting the rotation of the disk 93 in a counter-clockwise relation as seen in Fig. 5. The front of the disk has spaced studs 98 and 99, the spring 96 normally holding the disk in a manner to place the stud 98 against one side of the bracket 91. However, when the disk is rotated in a counter-clockwise direction per Fig. 5, its limit of rotation will be reached when the stud 99 meets the other side of the bracket. As seen in Fig. 5, the back of the disk 93 is made with a circular series of teeth 100, these tripping a detent 101 which is spring-backed as indicated at 102. The detent is pivoted with its lower end in the bracket 92, so as to be rockable in a rearward direction on the slight rearward pressure of a button 103 whose spindle 104 passes through the front wall of the housing to meet the detent 101. Thus, in case the disk 93 has been rotated in the counterclockwise direction per Fig. 5 to a given point, a slight pressure on the button 103 will cause the detent 101 to relax its pressure on the disk, in which event the spring 96 will quickly draw the same around to the original position. Outwardly, the effect of this action is to constitute the button 103 as a control for the pointer 15, so that after the same has been swung to a given point along the scale 17, the

immediate return of the pointer to the origin of its travel—or zero on the scale—will be accomplished by merely pressing the button 103. The spindle 90 carries a suitable tripping device 104 for the hammer 105 of a bell 106, so that the bell may be struck when the pointer 15 has swung to a predetermined forward limit on the scale 17.

The rotation of the disk 93 in the counter-clockwise direction as seen in Fig. 5 is primarily procured by means of a chain 110 rising over a pulley 111 which is mounted alongside the bracket 92. The lower end of the chain is secured to an eye screw 112 carried by a pin 113 extending back from the inner base portion of the right-hand arm 25, such pin passing through an open slot 114 in the inner base portion of the companion arm 25. Thus, the down swing of the said inner base portions in response to the gather of the arms 25 will cause the pin 113 to descend and pull on the chain 110. Above the pulley 111 the chain rises to the left-hand side of the spindle 90 as seen in Fig. 3 and is trained toward the right over a sleeve 115 freely mounted on the spindle behind the hub 94 of the disk 93. Spacedly behind the sleeve 115 a block 116 is made fast to the spindle, such block having a forward stud 117. Likewise, the rear end of the sleeve 115 has a stud 118. When the sleeve is rotated in a counter-clockwise direction, the stud 118 meets the stud 117 from behind and thus impinges on the block 116 to cause the rotation of the spindle in the same direction. The chain 110, as trained over the sleeve 115, is secured on the opposite side thereof to a stud 119. Thus, the down-pull on the chain serves to rotate the spindle, but the loose connection of the sleeve 115 between studs 118 and 117 enables the chain to be pulled up again without effecting the extent to which the spindle has been rotated. In this manner, the reading on the dial remains stationary after the muscle test has been relaxed. In order that the chain 110 may be kept taut, a spring 120 is extended from the stud 119 to a suitable connection 121 on the frame.

In order that the grip and pull-up tests may also register on the dial, a connection from the slide 40 is made to the chain 110. Thus, a screw eye 122 is mounted on the slide for the connection of the lower end of a chain 123. The latter passes under a pulley 124 carried by the angle bar 41 to rise in the direction of the chain 110 and be connected thereto in front of the pulley 124. A light spring 125 from the bracket 92 suspends the chain 123 against a tendency to slacken on the retraction of the slide.

In order that the arcuate slots 14 in the front of the housing may be closed to discourage tampering, plates 126 behind the front wall are provided as covers for the slots. Each plate is pivoted on a screw 127, and has a slot 128 for the passage of the knob shanks 13.

As the machine is coin-controlled, it is intended that the gather of the arms 25 and the advance of the slide 40 be locked until released by the insertion of the coin. The front of the machine has the usual slot 130 by way of which a coin is insertible to run down a chute 131 and strike a paddle 132 pivoted at 133 from a rocker bar 134. This bar is T-shaped and pivoted at its junction on a pin 135 projected rearwardly from the front wall of the housing. That end of the rocker bar to which the paddle is pivoted is enlarged as indicated at 136 to serve as a weight, and such

end is supported from the said front wall by a coil spring 137. The ends of the rocker bar are notched as indicated at 138 to form seats for rearward studs 139 projecting from the upper portions 5 of the arms 25, such studs serving as limits to the rocking of the bar 134 in a counter-clockwise direction. However, when the rocker bar is so positioned it forms end stops for the studs 139 to prevent the gathering action of the arms 25.

10 On the other hand, when the rocker bar is actuated for a short distance in a clockwise direction, it releases the studs, so that the arms 25 may be gathered.

Ordinarily, the rocker bar 134 is maintained 15 in the locking position for the studs 139 by being supported at its weighted end. The support consists of a detent 140 which extends along the rear side of the rocker bar 134 and is medially pivoted on the pin 135. The detent 140 is weighted 20 at one end as indicated at 141, such end being opposite from the one at which the rocker bar 134 is weighted. The detent normally rests at the weighted end on the related stud 139, being formed with a flared recess 142 for this purpose. 25 The opposite end of the detent is pointed, and normally forms a support for a hook 143 which forms an upward extension of the paddle 132. The hook 143 therefore serves to hold up the weighted end of the rocker bar 134. The latter 30 has its medial arm 134a seated in a side slot 144 made in the slide 40, so that such medial arm occurs directly behind a wall bracket 145. The medial arm therefore forms a lock against the advance of the slide, and is backed by the wall bracket 145 in this respect.

With the parts arranged as just described, it is intended that the drop of the coin in the chute 131 strike the paddle 132 with sufficient force 40 to swing the same inwardly, so as to both create a space for the coin to drop into the bottom of the housing and back the hook 143 off the detent 140. With the rocker bar 134 so divested of its suspension from the detent 140, the rocker bar will swing in a clockwise direction to a sufficient extent to release the studs 139 for inward travel. The rocking action of the rocker bar will at the same time swing its pendent arm 134a 45 out of the slide slot 144, releasing the slide for its forward movement.

50 The testing units may now be operated. However, the testing movements are employed as they advance to lock the machine against a repetition of the tests until the next coin has been deposited.

55 It is noted that the pointed end of the detent 140 is rounded underneath as indicated at 146 to form a rising cam; and the hook 143 is extended inwardly with a weight 147 to urge the hook 143 in the direction of such cam; a pin 148 from the portion 136 serving as an inward limit for the swing of the hook. Now, as the muscle 60 test is taken, the left-hand stud 139—as seen in Fig. 5—urges the detent upwardly by action against the inner wall of the slot 142, so that the pointed end of the detent is soon lowered to the extent of being again caught by the hook 143.

The weight of the hook and enlargement 136 is now over-balanced by the weight 141, so that the studs 139 are again locked, and the paddle is 65 back in its normal place under the chute. The detent is formed with a slot 149 through which extends a stud 150 projecting back from the rocker bar 134, the object of this arrangement being for the assurance of full clearance by the 70 corresponding end of the rocker bar of the re-

75

lated stud 139 in case of a prolonged advance of the arm 25.

The mechanism just described procures the resetting of the hook 143 by the clockwise movement of the detent. The same movement is induced by a spring backed rod 151 extending from the slide block 69 to the weighted side of the detent 140, where the rod makes connection by entering sidewise into a bolt head 152 secured to the detent. The advance of the slide for a grip or pull-up test now acts in the same manner as the inward movement of the muscle-test arms 25, that is, to lift the weighted portion of the detent. The spring backing 153 of the rod 151 is of course provided to prevent hardship when the advance of the slide is prolonged.

The arrangement described above, while conventional in basic respects, is novel in the relation of its units to simply and conventionally interpose the extra resistance for all the tests, by the simple pull of an auxiliary knob. In addition, a simple coin control is employed which is self-locking and resetting irrespective of the position of the machine, so that tampering with or abuse of the machine is prevented. While the parts involved may seem fairly numerous, they are as few as can be employed to accomplish all the objects and operations of the machine, and they are of a nature to operate efficiently over a long period without the need of attention or repair. No mechanism is under tension while the machine is not in use, so that adjustments or replacements are not necessary from time to time. Finally, the mechanism is compactly grouped, and occasions no radical increase in cost over machines of a similar nature.

While I have described the invention along specific lines, various minor changes and refinements may be made without departing from its principle, and I desire to consider all such changes and refinements as coming within the scope and spirit of the appended claims.

I claim:

1. In a strength-testing machine, means movable by human effort, a resistance to the movement of said means, a second resistance, and a mechanism to connect the second resistance to augment the first one, said means comprising a pair of arms having a concerted movement, a support for the arms, the first resistance comprising a spring from one of the arms leading and permanently attached to the support, said second resistance comprising a spring leading from the other arm to the support without being attached thereto, the support including a hook in the lateral path of the related end of the second mentioned spring, said mechanism comprising a manually operable shifter for said second mentioned spring to shift the same into engagement with said hook, and means to normally retain the second mentioned spring against the hook-engaging movement.

2. In a strength-testing machine, means movable by human effort, a resistance to the movement of said means, a second resistance, and a mechanism to connect the second resistance to augment the first one, said means comprising a pair of arms having a concerted movement, a support for the arms, the first resistance comprising a spring from one of the arms leading and permanently attached to the support, said second resistance comprising a spring leading from the other arm to the support without being attached thereto, the support including a hook in the lateral path of the related end of the second men-

tioned spring, said mechanism comprising a manually operable shifter for said second mentioned spring to shift the same into engagement with said hook, and a light spring directed from the hook-engaging end of the second mentioned spring to the support to normally retain the second mentioned spring against the hook-engaging movement.

3. In a strength testing machine, a housing, a pair of arms inside the same and having a concerted movement, a pair of manually-actuated controls outside the housing and connected through the same to the respective arms, a spring leading from one of the arms to the housing and serving as a resistance to said movement, a second spring leading from the other arm to the housing without being attached thereto, a hand control outside the housing, and means inside the latter and operable by said hand control to attach the second spring to the housing and impose an added resistance to said movement.

4. The structure of claim 3, the housing having a hook in the lateral path of the free end of said second spring, and said means comprising a shifter effective on the second spring to engage its free end with said hook.

5. The structure of claim 3, the housing having a hook in the lateral path of the free end of said second spring, said hand control comprising a pull-knob extended into the housing with a rod, and said means comprising an oblique cam positioned alongside the second spring, the pull of said knob causing said cam to impart a lateral urge on the adjacent spring and engage the free end thereof with said hook.

6. In a strength testing machine, a muscle-test unit involving a pair of arms having a joint lateral movement, a support, a spring from one arm to the support and constituting a resistance to said movement, a second spring from the other arm and attachable to the support to constitute an added resistance to said movement, a grip-test unit involving a bar having a forward movement, a third spring from said bar to the support and constituting a resistance to said forward movement, a fourth spring from the support to a point alongside the bar, a carrier for the free end of the fourth spring and movable to a position in the path of the bar to constitute the fourth spring an added resistance to its movement, a hand control, and means operable by the latter to concurrently attach the second spring to the support and move the carrier as stated, whereby to impose added resistance to both units by means of the single control.

7. The structure of claim 6, said hand control having a single operative movement.

8. The structure of claim 6, said hand control comprising a pull rod, and a pair of cams carried by the pull rod, one cam being effective on the operation of the rod to urge the second spring into attachment with the support, and the other cam acting at the same time to crowd the carrier into the position subject to interception by said bar.

9. In a strength testing machine, a muscle-test unit involving a pair of arms having a joint lateral movement, a support, a spring from one arm to the support and constituting a resistance to said movement, a second spring from the other arm and attachable to the support to constitute an added resistance to said movement, a grip-test unit involving a bar having a forward movement, a third spring from said bar to the support and constituting a resistance to said forward move-

ment, a fourth spring from the support to a point alongside the bar, a carrier for the free end of the fourth spring and movable to a position in the path of the bar to constitute the fourth spring an added resistance to its movement, a pull-up test unit involving a downwardly-movable rod, a cam operated by the latter and effective on the bar to

5 advance the same against the resistance of said third spring, a hand control, and means operable by the latter to concurrently attach the second spring to the support and move the carrier as stated, whereby to impose added resistance to the three units by means of the single control.

JOHN G. JANSEN.
